US0D1094288S

(12) **United States Design Patent** (10) **Patent No.:** **US D1,094,288 S**
(45) **Date of Patent:** **** Sep. 23, 2025**

(54) **POWER MODULE**

(71) Applicant: **Industrial Technology Research Institute**, Hsinchu (TW)

(72) Inventors: **Yuan-Cheng Huang**, New Taipei (TW); **Ji-Yuan Syu**, Kaohsiung (TW); **Po-Kai Chiu**, Taoyuan (TW); **Kuo-Shu Kao**, New Taipei (TW)

(73) Assignee: **Industrial Technology Research Institute**, Hsinchu (TW)

(**) Term: **15 Years**

(21) Appl. No.: **29/897,856**

(22) Filed: **Jul. 19, 2023**

(30) **Foreign Application Priority Data**

Jun. 29, 2023 (TW) 112303274

(51) **LOC (15) Cl.** **13-03**

(52) **U.S. Cl.**

USPC **D13/182**

(58) **Field of Classification Search**

USPC D13/103, 107, 108, 110, 112, 118, 133, D13/146, 162, 182; D14/224, 224.1; D6/580

CPC H01M 50/103; H02J 50/10
See application file for complete search history.

(57) **CLAIM**

The ornamental design for a power module as shown and described.

DESCRIPTION

FIG. 1 is a perspective view of a power module showing our new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken line portions of the power module in FIGS. 1-7 represent unclaimed portions of the claimed design and form no part thereof.

1 Claim, 5 Drawing Sheets
